(57) **CLAIM**

The ornamental design for an insert aligning head for a dental handpiece, as shown and described.

DESCRIPTION

FIG. 1 is a right front perspective view of an insert aligning head for a dental handpiece.

FIG. 2 is a left back perspective view of the insert aligning head for a dental handpiece.

FIG. 3 is a front view of the insert aligning head for a dental handpiece.

FIG. 4 is a right side view of the insert aligning head for a dental handpiece.

FIG. 5 is a back view of the insert aligning head for a dental handpiece.

FIG. 6 is a left side view of the insert aligning head for a dental handpiece.

FIG. 7 is a top view of the insert aligning head for a dental handpiece.

FIG. 8 is a bottom view of the insert aligning head for a dental handpiece; and,

FIG. 9 is a close-up perspective view of region 9 of FIG. 2. The portions shown in broken lines in the drawings illustrate an environment and are not part of the claimed design.
